UTILITY CONTROL DESK

Albert Parmet, West Hempstead, N. Y., assignor to Par-Metal Products Corp., Long Island City, N. Y., a corporation of New York

Application May 3, 1954, Serial No. 30,305

Term of patent 14 years

(Cl. D26—5)

Fig. 1 is a front perspective view of a utility control desk showing my new design, the left side of the drawer pedestal section having a bayed portion similar to that shown on the right side but without the louvers.

Fig. 2 is a rear elevational view thereof.

I claim:

The ornamental design for a utility control desk, as shown and described.
